(57) CLAIM

I claim, the ornamental design for a mattress including mattress handles, as shown and described.

DESCRIPTION

FIG. 1 is a perspective view of a mattress including mattress handles showing my new design;

FIG. 2 is a top down view of the mattress including mattress handles of FIG. 1;

FIG. 3 is a foot end view of the mattress including mattress handles of FIG. 1;

FIG. 4 is a head end view of the mattress including mattress handles of FIG. 1; and,

FIG. 5 is a right-side view of the mattress including mattress handles of FIG. 1.

The left-side view of the illustrated mattress including mattress handles is not shown because it is mirror image of the right-side view shown in FIG. 5.

The mattress including mattress handles includes a symbolic break along its length and width in broken lines. The broken break lines and the area between the break lines form no part of the claims design.
